(57) **CLAIM**

The ornamental design for a tension rod, as shown and described.

DESCRIPTION

FIG. 1 is a front, top perspective view of a tension rod, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 2; and,

FIG. 11 is a left, front, and top perspective view thereof, shown in a disassembled configuration of use.

The dashed broken lines of the tube in FIG. 11 are for the purposes of illustrating portions of the tension rod, that form no part of the claim design.

The dash-dot-dash broken lines are for annotating enlarged views, and form no part of the claimed design.
